UNITED STATES PATENT OFFICE.

SAMUEL H. LIGHTON, OF LOUISVILLE, KENTUCKY.

DESIGN FOR AN AIR-GRADE OR VENTILATOR.

SPECIFICATION forming part of Design No. 15,618, dated December 16, 1884.

Application filed September 1, 1884. Term of patent 3½ years.

To all whom it may concern:

Be it known that I, SAMUEL H. LIGHTON, a citizen of the United States, residing at Louisville, in the county of Jefferson and State of Kentucky, have invented and produced a new and original Design for Air-Grates in Buildings which Require Ventilation, of which the following is a specification.

Reference is made to the accompanying drawing, which forms a part of this specification.

The figure is a view of my design for air-grates as seen in side elevation, consisting of perforated fretwork by combination of rings and bars of different sizes and numbers, substantially as shown in the drawing.

The design-key consists of one small ring laid within a larger ring, and nearly equidistant from the inner circumference of the larger ring and the common center. The rings are connected by four short radial bars.

The design, as a whole, consists of a rectangular frame, within which multiples of the key are so arranged that the centers of four larger rings would fall on the four corners of 25 imaginary squares, and the larger rings would overlap, so that the outer circumference of one ring would be tangent to the inner circumference of the adjoining larger rings, and the short radial bars would be at an angle of 30 forty-five degrees to the sides of the squares.

I claim—

The design for a ventilator or air-grate, consisting of a combination of rings and bars within a frame, substantially as described and 35 shown.

In testimony whereof I have affixed my signature in the presence of two witnesses.

SAM'L. H. LIGHTON.
